UNITED STATES PATENT OFFICE.

ERNEST P. FARLEY AND JOHN L. RIFER, OF PORTLAND, OREGON.

SLIDING-DOOR FASTENER.

1,145,409.

Specification of Letters Patent.

Patented July 6, 1915.

Application filed April 18, 1913. Serial No. 762,109.

To all whom it may concern:

Be it known that we, ERNEST P. FARLEY and JOHN L. RIFER, citizens of the United States, residing at Portland, in the county of Multnomah and State of Oregon, have invented new and useful Improvements in Sliding-Door Fasteners, of which the following is a specification.

This invention has relation to sliding doors and refers particularly to releasing doors, such as disclosed in Patent No. 1,056,014, heretofore obtained by us on March 18, 1913.

The object of this invention is to provide, in doors of the above specified character, improved means for effecting the locking of the door in position, so as to coöperate with the above devices to produce a door-mechanism of greater utility and reliability than has heretofore been obtained. With this object in view we have hereinafter clearly and concisely described such combinations of devices through the medium of which we aim to produce the above result, and drawings are hereto appended for the purpose of facilitating the perusal of said description.

In the drawings: Figure 1 is a view of a portion of a car and car door with the locking lever in open position. Fig. 2 shows a latch-mechanism for the operating lever of the device.

The door 1 is mounted to freely operate over the sill 18, and is adapted to be locked into position by means of a locking lever 10 which is suitably pivoted to the door. The lower end of the lever 10 has an angular offset portion 10^a adapted to lie parallel with the outer surface of the wall of the car. The sill 18 is supported by means of sill-brackets 19 of a peculiar shape adapted to guide the door to its seat to permit of the latching of the angular offset portion 10^a. The lower portion 19^a of the inner face of said bracket is vertically directed and so spaced from the door frame as to leave room enough for the door to slide on the sill. This lower portion extends substantially one-third the height of the bracket 50 above the sill. The second portion 19^b

slants outwardly at a suitable angle, and the top portion 19^c thence continues in a vertical direction.

The door in seating into locked position, first enters the portion 19^c, as shown in Fig. 1, then inward and downward past the portion 19^b, thence downward in the portion 19^a to its seat, when the locking lever 10 can be latched into position. When the door is seated, the lever 10, which is shown as open in Fig. 1, is closed so that the angular offset portion 10^a extends beneath the sill 18 substantially as shown in Fig. 2.

A lug projects from the wall of the car beneath the sill 18 as shown in Fig. 2, upon which is pivotally mounted a latch lever 22 having an operating handle at one side and a latch at the opposite side, which is adapted to hook over the lower end of the angular offset portion 10^a and thus latch the lever 10 into closed position. To properly maintain the latch in engagement with the angular offset portion 10^a of the lever 10, a suitable coiled spring is mounted between the outer surface of the wall of the car and the inner portion of the handle of said latch-lever. To release said latch-lever from engagement with the angular offset portion 10^a of the lever 10, it is only necessary to press the handle of the latch-lever in toward the outer surface of the wall of the car against the action of the coiled spring, when the lever 10 can readily be raised into open position as shown in Fig. 1.

We claim:

In a device of the character described, the combination with a car having an angular door sill, of a sliding door seated on said sill, a locking lever pivoted to said door having an angular inturned portion with an end section at right angles to said inturned portion, said inturned portion adapted to seat beneath said sill and said right angle section adapted to vertically depend parallel with and adjacent the wall of the car, a lug projecting from said car, locking means pivoted in said lug having an outer hook portion at one end adapted to hook over the lower end of said depending right angular section of said lever to lock the same to its

seat, having a manipulating handle at the opposite end adapted to operate said locking means to unlock said lever, and spring means mounted between the wall of the car and said locking means adapted to keep the hooked end of said locking means in engagement with said right-angular depending section of said locking lever.

In testimony whereof, we have hereunto affixed our signatures.

ERNEST P. FARLEY.
JOHN L. RIFER.
